UNITED STATES PATENT OFFICE

WILLIAM S. GILBERT, OF DETROIT, MICHIGAN, ASSIGNOR TO MORGAN & WRIGHT, A CORPORATION OF MICHIGAN

DESIGN FOR A TIRE

Application filed April 12, 1930. Serial No. 35,231. Term of patent 7 years.

To all whom it may concern:

Be it known that I, WILLIAM S. GILBERT, a citizen of the United States, residing at Detroit, county of Wayne, and State of Michigan, have invented a new, original, and ornamental Design for Tires, of which the following is a specification, reference being had to the accompanying drawing, forming part thereof, wherein—ment of a tire showing my new design, and Fig. 2 is an edge view of a portion of the tire.

I claim:

The ornamental design for a tire as shown. Signed at Detroit, in the county of Wayne and State of Michigan, this 7th day of April, 1930.

WILLIAM S. GILBERT.
